Richard Walker
Inventor Patent

The Schedule referred to in these Letters Patent and making part of the same containing a description in the words of the said Richard Walker himself of his improvement in the construction of Water Wheels & applying Water thereby.

To all to whom these presents shall come
Be it known that I (Richard Walker) of Linton in the County of
Hampshire State of New Hampshire have invented a new & useful improve-
ment in the construction of Water Wheels, in the application of Water
to the wheel, & that the following, is a full & exact description of the
construction & operation of the said Wheel as invented by me.

The wheel I present by the drawing & Model is a plain iron wheel
one foot high with an iron shaft four inches in diameter the shaft
is to stand perpendicular on a pivot in the bottom of the conductor.
From the center of the wheel around the shaft extends a cast iron
tube cylinder downwards into the conductor upon the top of which
is to be a circular plate this plate the cylinder passes so as to
make it water tight. The cylinder about one foot in diameter
with the lower end open receives the water as it is forced from the
conductor & conducts it into the center of the wheel. From the center
of the wheel the water is forced out at the rim thro' three semi-cir-
cular brackets or hollow arms to the opposite parts of the rim. The
brackets or winding outlets are three inches wide by nine deep mak-
ing the column of water passing thro' the wheel nine inches square.

The sweep of the inside of said brackets arms or outlets is the sweep
of the semidiameter of the wheel & the continual pressure of water on the
outer circle gives the wheel its motion. Further said wheel may
be built of either wood or cast iron & when built for tide water is
to present an entire smooth surface excepting the outlets in the rim.
A well made well made water outlet of water head may be made
for ordinary purposes with only hollow semicircular arms. Further

chain-tire plates varying, the size of each wheel from two feet to twenty-five, in proportion to the speed required to carry the size and number of buckets from one to ten, in proportion to the strength required. The principle I claim as my invention is the taking in the water on the inner side of the wheel with an upward bearing, by which the wheel is reduced of its own specific gravity, to the full amount of the force of the column, taken in by the construction of the wheel to make the water act with full force from the center outward on every part alike at once, by the same time those said buckets or semicircular mouths by which the wheel gains its motion.
